UNITED STATES PATENT OFFICE.

HARRY E. BRICKER, OF WEST VIEW, PENNSYLVANIA, ASSIGNOR TO NATIONAL METAL PRODUCTS COMPANY, OF PITTSBURGH, PENNSYLVANIA, A CORPORATION OF PENNSYLVANIA.

SPACING BAR.

Application filed May 17, 1924. Serial No. 713,958.

To all whom it may concern:

Be it known that I, HARRY E. BRICKER, a citizen of the United States, residing at West View, in the county of Allegheny and State of Pennsylvania, have invented certain new and useful Improvements in Spacing Bars, of which the following is a specification.

My invention consists of an improvement 10 in spacing bars for reinforced concrete construction for use in connection with transverse floor or slab members. It has in view to provide a supporting and spacing bar for the reinforcing or anchoring members 15 adapted to maintain the same at the desired location within the body of concrete, to fixedly and positively hold and locate the members, and to maintain its own supporting position within the concrete body 20 without tendency to shift.

It consists generally of a channel member having horizontally disposed lateral flanges of sufficient area to provide continuous bearing portions in the concrete, said flanges 25 being fitted at intervals and pressed downwardly to provide temporary supporting pedestals, and with partly severed tongues slotted from the flat web portion of the channel member for engagement with the 30 reinforcing anchoring members.

The device in general, is similar in its intended use to that shown in patent of Metzger #1,421,807. Its object is to provide, in a single integral member, features of improvement in construction adapted to produce a more serviceable device, with greater economy and facility of manufacture.

In the drawings, illustrating one preferred embodiment of the invention;

Fig. 1 is a perspective view showing a 40 portion of my improved spacing bar as used with the cross reinforcing members;

Fig. 2 is a view in side elevation, showing the bar as applied and with relation to the 45 supporting form;

Fig. 3 is a plan view of Fig. 2;

Figs. 4 and 5 are cross sections on the lines IV-IV and V-V respectively of Fig. 2.

The bar, of any desired length, is of channel form pressed from sheet metal, having a middle upper web 2, downwardly extending preferably outwardly flared sides 3-3, and oppositely extending lateral hori-

zontal flanges 4-4, of ample width to provide a continuous broad bearing footing in the concrete. At somewhat long separated intervals, the flange 4 is severed from the base portion of side 3, at opposite sides, by suitable slitting dies, effecting severance of the flange from the base of the side, as indicated at 5. The severed portion of the flange is bent downwardly, forming a lowered shoe 6, having a flat under face parallel with the under side of the integral portions of flange 4, and adapting the bar to be supported upon the upper surface of the usual temporary form boards 7, as clearly indicated in Figs. 2, 4 and 5.

By this construction, the main body portion of the bar is located sufficiently far above the form, more or less, according to the thickness of the concrete floor, to locate it at the desired position and with the flanges 4 spaced well above the form, so as to permit free flow of the concrete underneath and to the interior cavity of the channel, while at the same time completely embedding and supporting the entire bar by its flanges and also by web 2 within the body of the semi-fluid concrete.

By reason of the broad supporting areas of the flanges 4, any tendency to sag or sink through the concrete, due to superimposed weight between the spaced pedestal 6, is positively avoided. A further and important advantage in manufacture is that, in slitting the pedestals from the sides, the shearing dies act against a flat surface, which is at right angles to their vertical movement, avoiding the objectionable tendency to lateral strain and rapid wear of the slitting dies. I have found in practice that, where such dies are used, acting against an inclined surface, as in an angle form of bar, there is great difficulty in effecting accurate slitting, with accompanying distortion and wear and necessary frequent repair or renewal of the cutting dies.

A further advantage is that the original flat and parallel relationship of the flange is maintained in the severed portion, without necessity of any twisting or other bending, producing a supporting pedestal or shoe of the best available construction.

The web 2 of the channel is also slotted at desired intervals or locations, as indicated at 11, to form the upwardly extending

arched tongue member 8, left integral at one end with the web, as indicated at 9, forming a curved holding tongue for the reinforcing bar 10.

5 A further advantage in the use of the channel shape is that the web 2, being originally flat, provides a transversely flat bearing surface underneath the tongue, so that it will positively and snugly embrace the bar 10 and may be bent downwardly thereover to form a good holding contact, as will be readily understood. The tongues 8 may be slit out of the web at desired intervals by suitable mechanism, either separately or 15 simultaneously, with the formation of the pedestal 6. Ordinarily, the latter are provided at or near the end portions of the bar or standard of any desired length, with the intervening unsupported portion which is 20 adapted to lie in the concrete and be supported thereby, as explained above, due to the broad bearing character of the horizontal flanges 4.

The device may be made of any suitable 25 dimensions, of comparatively thin sheet metal, and, dependent on the dimensions of the concrete floor, may be easily located and spaced by the user, dependent on the local conditions. The spacing bar as thus made 30 is comparatively simple, economical in construction, and well adapted to perform the desired functions in a satisfactory manner, and overcomes the rather serious objections

to other forms of spacing bars heretofore used.

Having described my invention, what I claim is:

1. A spacing bar for concrete reinforcement consisting of a sheet metal channel member having a flat middle web, sides and laterally extending flanges having integral portions severed from the sides and pressed downwardly providing longitudinal flat faced supporting shoes with depressed bearing portions parallel with the lateral flanges, 45 and having partially severed holding tongues extending upwardly from the middle of the channel web.

2. A spacing bar for concrete reinforcement consisting of a sheet metal channelled member having a flat middle web, outwardly flaring sides, and laterally and oppositely extending flanges parallel with the web having integral portions severed from the sides by slitting along their bases and pressed downwardly providing longitudinal flat faced supporting shoes with depressed flat bearing portions parallel with the lateral flanges and merging thereinto by curved 60 end portions, and having partially severed transversely flat holding tongues extending upwardly from the middle of the channel web.

In testimony whereof I hereunto affix my signature.

HARRY E. BRICKER.
